UNITED STATES PATENT OFFICE

148,290

DESIGN FOR A FLOWER HOLDER

Orien T. Dixon, Miami, Okla.

Application January 28, 1946, Serial No. 126,040

Term of patent 7 years

(Cl. D35—3)

To all whom it may concern:

Be it known that Orien T. Dixon, a citizen of the United States of America, residing at Miami, in the county of Ottawa and State of Oklahoma, has invented a new, original, and ornamental Design for a Flower Holder, of which the following is a specification, reference being had to the accompanying drawing, forming part thereof.

Figure 1 is a perspective view of a flower holder showing my new design.

Figure 2 is a transverse sectional view of the flower holder, and

Figure 3 is a longitudinal sectional view of the flower holder.

I claim:

The ornamental design for a flower holder, as shown.

ORIEN T. DIXON.
